(57) **CLAIM**

The ornamental design for a foldable wireless charging support as shown and described.

DESCRIPTION

1.1 is a front elevational view of a foldable wireless charging support showing our new design;

1.2 is rear elevational view thereof;

1.3 is a left side elevational view thereof;

1.4 is a right elevational view thereof;

1.5 is a top plan view thereof;

1.6 is a bottom plan view thereof;

1.7 is a front, top, and right side perspective view thereof;

1.8 is a rear, top, and left side perspective thereof; and

1.9 is a front, top, and right side perspective view of the foldable wireless charging support where the foldable wireless charging support is in an unfolded state.

The broken lines in the drawings depict portions of the foldable wireless charging support that form no part of the claimed design.
